(57) **CLAIM**

The ornamental design for a street light retrofit assembly, as shown and described.

DESCRIPTION

FIG. 1 is a top perspective view of the street light retrofit assembly, showing our new design;

FIG. 2 is a bottom perspective view of the design illustrated in FIG. 1;

FIG. 3 is a front elevation view of the design illustrated in FIG. 1;

FIG. 4 is a rear elevation view of the design illustrated in FIG. 1;

FIG. 5 is a right side elevation view of the design illustrated in FIG. 1;

FIG. 6 is a left side elevation view of the design illustrated in FIG. 1;

FIG. 7 is a top plan view of the design illustrated in FIG. 1; and,

FIG. 8 is a bottom plan view of the design illustrated in FIG. 1.

Portions of the drawings executed in broken lines in the various views are provided to illustrate environment and do not form a part of the claimed design.
